Primary Examiner — Marissa J Cash*Assistant Examiner* — Altaira J Swangin(74) *Attorney, Agent, or Firm* — Seager, Tufte & Wickhem LLP(57) **CLAIM**

The ornamental design for a cosmetic kit, as shown and described.

DESCRIPTION

FIG. 1 is a front, left, perspective view of a cosmetic kit showing the new design;

FIG. 2 is a front view thereof;

FIG. 3 is a rear view thereof;

FIG. 4 is a right side view thereof;

FIG. 5 is a left view thereof;

FIG. 6 is a top view thereof; and,

FIG. 7 is a bottom view thereof.

The cosmetic kit is shown with a symbolic break in its length. The appearance of any portion of the article between the break lines forms no part of the claimed design.

1 Claim, 7 Drawing Sheets# US D880,775 S
